UNITED STATES PATENT OFFICE.

FREDERICK D. SCHNEIDER, OF BEDFORD, OHIO.

HEATER.

1,054,944.

Specification of Letters Patent.

Patented Mar. 4, 1913.

Application filed October 13, 1911. Serial No. 654,434.

To all whom it may concern:

Be it known that I, FREDERICK D. SCHNEIDER, a citizen of the United States, resident of Bedford, county of Cuyahoga, and State 5 of Ohio, have invented a new and useful Improvement in Heaters, of which the following is a specification, the principle of the invention being herein explained and the best mode in which I have contemplated applying that principle, so as to distinguish it from other inventions.

My invention has reference broadly to means for carrying out a method for fulfilling with a minimum loss of thermal units, 15 the operation required in the transfer of heat from one agent to another.

To illustrate the application of the method, both preferred and modified structural combinations have been represented in 20 the drawings. As a specific exemplification of these combinations, and for the purpose of insuring a sufficiently intelligent consideration of the novelty of the inventive conception, more particular reference is 25 made to a water heater.

The said invention consists of means which are hereinafter fully described and particularly pointed out in the claims.

The annexed drawings and the following description set forth in detail certain means embodying my invention, the disclosed means, however, constituting as already intimated, only some of various mechanical forms in which the principle of my 35 invention may be applied.

Referring to the drawings:—Figure 1 is an elevation of a heater embodying my invention, the inclosing casing being shown in section. Fig. 2 is a similar view of a simplified modification. Fig. 3 is a similar view of still another modification. Fig. 4 is a section on line IV—IV of Fig. 3, looking in the direction of the arrows. Fig. 5 is a vertical section of a further modification corresponding in operation to the modification disclosed in Fig. 3. Fig. 6 is a section on line VI—VI of Fig. 5, looking in the direction of the arrows. Fig. 7 is another modification, corresponding in operation to the 45 modification disclosed in Fig. 2. Fig. 8 is a section on line VIII—VIII of Fig. 7, looking in the direction of the arrows.

Considering first the structure shown in Fig. 1, it will be noted that it comprises an 55 upright inclosing casing A, having a horizontal closed partition a', dividing it into

two divisions, a² and a³. Each of these divisions is provided near the top thereof with an outlet, a⁴ and a⁵ respectively, each communicating with the chimney a⁶. A pair 60 of gas burners B and b', of any approved type, are disposed at different heights within the casing, and as shown respectively near the bottom of the two divisions a² and a³. The upper of these burners, for a purpose 65 presently apparent, is preferably, though not necessarily, of smaller capacity.

A cold water inlet pipe C connects with one side of the casing, and enters at two points through the medium of a suitable T 70 c' and 90° elbow c², and a corresponding hot water outlet pipe D connects with the opposite side of the heater through the medium of a similar 90° elbow d' and T d². Communicating with the inlet T is the primary 75 hot water coil E. This, as shown, comprises three horizontal pipe-lengths connected by the return bends e' and e², and outside the casing with the elbow d'. The proximity of the lowermost coil E to the primary 80 burner B, and the length of this coil, should be such that the water will be raised to the desired temperature during its passage therethrough. A second coil F is disposed above the coil E, and connects with the cold water 85 inlet through the medium of the elbow c². This coil is preferably of greater length, comprising, for example, five horizontal pipe lengths suitably connected by the return bends f', f², f³ and f⁴. This coil constitutes, in accordance with my conception, 90 the warm water coil whereby the cold water entering it may be sub-heated by the residual heat of the primary burner B prior to its exit through the outlet a⁴, leaving the 95 chimney. The upper pipe length of the coil F extends without the casing, and communicates through the medium of two elbows with the inlet of a third coil G, which is disposed over the upper burner b'. This coil 100 may be of relatively smaller length, owing to the fact that the water entering it has been somewhat warmed, and as shown comprises merely two pipe lengths connected by the return bend g', the upper of which 105 passes out of the casing to connect with the hot water pipe D through the medium of the T d². It should now be noted that through the employment of this system of utilizing heat, a measurably smaller amount 110 emanating from the primary burner B, is wasted, so that that which does issue forth

through the outlet a^4 is reduced to a temperature considerably below that of the hot water passing through the pipe D. Consonantly, by reason of the fact that the upper secondary burner b' may be of smaller capacity, the waste heat therefrom will necessarily be a proportionately smaller amount. In consequence, a given supply of water passing through a heater constructed 10 after the manner of my invention, may be heated to a predetermined temperature with a measurably reduced loss of the heat carried by the particular heating agent.

The modification represented in Fig. 2 is 15 merely one of simplification, and specifically through the omission of the partition a' , whereby the gases of combustion from both of the burners may pass into the chimney through the single opening a^5 .

20 The modification to which Figs. 3 and 4 relate, includes as a means for heating the upper hot water coil, a by-pass construction as a substitute for the upper burner construction. To this end, this form is provided with an angular partition p' , best seen in Fig. 4. The horizontal portion of this partition extends completely across the casing, as clearly shown in Fig. 3, but is spaced some distance from the front thereof, as in turn best seen in Fig. 4, and at that point the depending portion of the partition is positioned. Another horizontal partition member p^2 is secured to the front of the casing somewhat above the horizontal portion of the partition p' , as clearly appearing in Fig. 4. This partition serves the obvious function of a baffle-plate whereby the gases of combustion rising in the by-pass B P are turned rearwardly in order to more effectively envelop the coil G. Figs. 3 and 4, it will be noted, represent a double series of coils, either series of which, however, corresponds precisely as concerns its operative position, with that shown in Figs. 1 and 2. 45 During the operation of a heater constructed in accordance with this by-pass modification, the gases of combustion from the primary burner B will simultaneously rise in the lower division a^2 of the casing, and in 50 the by-pass B. P. The warm water coils F are sub-heated in an identical manner by the gases having their exit through the outlet a^4 , whereas the water in the upper hot water coils G is raised to the desired temperature 55 by the gases of combustion rising through the by-pass B P, as will be readily understood.

The construction of the modified heater shown in Figs. 5 and 6 is designed to have 60 its upper hot water coil heated through the medium of gases of combustion rising in a by-pass very similar to that disclosed in connection with the two figures considered in the previous paragraph. The casing in 65 this form I have designated by the refer-

ence letter H, the horizontal partition as h' , and the two outlets leading to the chimney as h^4 and h^5 respectively. The coils in this modification have, however, a somewhat different construction, being flat and of a width but slightly less than that of the width of the heater. The lower hot water coil, intermediary warm water coil and upper hot water coil, have been designated respectively by the reference characters K, L, M. The arrangement of the coils is furthermore such that the intermediary inclined portions are alternately spaced from the front and rear of the casing, in order that the rising gases of combustion may be caused to take a sinuous course on their way to the chimney. This will be apparent from an inspection of Fig. 6. Otherwise the operation of a heater so constructed is identical with that described in connection with Figs. 3 and 4.

70 The final modification represented in Figs. 7 and 8 embodies all the details of construction shown in Figs. 5 and 6, save the specific by-pass construction with its partitions. The manner of heating the several superimposed coils corresponds to that disclosed in Fig. 2, and consists in the employment of the primary and secondary burners B and b' , positioned respectively below the lower hot water coil K and the upper hot water coil M. The gases of combustion from these are designed to find their exit through the common outlet h^5 .

80 Having fully described my invention, what I claim and desire to secure by Letters Patent is:—

1. In an apparatus for heating and causing the circulation of a fluid, a closed end-less conduit system which includes a conduit having an upward inclination from its inlet to its discharge end, a second conduit located above the first and having an upward inclination from its inlet toward its outlet end, a third conduit having an upward inclination from its inlet to its discharge end, a duct connecting the outlet end of the second mentioned conduit and the intake end of the third mentioned conduit, a duct connecting the discharge end of the first mentioned conduit and the outlet end of the third mentioned conduit, and heating means located below said conduits.

85 105 110 115 120 125 130

2. In an apparatus for heating a fluid in a series-circuit-system, the combination of a heating chamber and means for producing heat therein, with an enveloped heating conduit constituting a part of such series-circuit-system and comprising a plurality of members connected in series, viz., a fluid receiving conduit positioned below and having a continuously upward inclination from its inlet end, a second conduit positioned in said chamber and having a continuously upward inclination from its inlet end, a third conduit positioned above and having a con-

tinuously upward inclination from its inlet end, and a pair of ducts respectively connecting the discharge ends of the first and third mentioned conduits with the intake and outlet ends of the second mentioned conduit.

3. A heater comprising a casing, a partition therein, distinct means for applying heat on opposite sides of said partition, a chamber provided with an inlet and an outlet and positioned adjacent one of said heating means, a second chamber provided with an inlet in communication with said first mentioned inlet and an outlet, said second chamber positioned beyond said first mentioned chamber, and a third chamber positioned beyond said second mentioned chamber and on the opposite side of said partition, said third chamber having an inlet in communication with the outlet of said second chamber and an outlet in communication with said first mentioned outlet.

4. A heater comprising a casing, a partition therein, distinct means for supplying heat to opposite sides of said partition, a chamber provided with a cold-water inlet, and a hot water outlet, and positioned on one side of said partition, a second chamber provided with a cold-water inlet and a warm water outlet, and positioned above said first mentioned chamber, and a third chamber in communication with said warm water outlet, and positioned on the other side of said partition, said last mentioned chamber being provided with a hot water outlet.

5. A heater comprising a casing, means for applying heat within said casing, a chamber provided with a cold-water inlet, and a hot water outlet, and positioned adjacent said heating means, a second chamber provided with a cold-water inlet and a warm water outlet, and positioned adjacent said first-mentioned chamber, separate means for applying heat within said casing, and a third chamber in communication with said warm water outlet, and positioned adjacent said separate heating means, said last-mentioned chamber being provided with a hot water outlet.

6. A heater comprising a casing, a plurality of heating means therein, a chamber adjacent one such heating means and provided with a cold water inlet and an outlet, a second chamber adjacent said first mentioned chamber and provided with a cold-water inlet and an outlet, a third chamber communicating with said last-mentioned

outlet, and itself provided with an outlet, said chamber located adjacent another such heating means.

7. A heater comprising an inclosing casing, a plurality of burners disposed therein, a chamber disposed over one such burner and provided with a cold-water inlet and an outlet, a second chamber disposed above said first-mentioned chamber and provided with a cold-water inlet and an outlet, a third chamber over another of such burners and communicating with said second mentioned outlet, said third chamber itself provided with an outlet, and a pipe communicating therewith and with said first-mentioned outlet.

8. A heater comprising a casing, a pair of burners disposed at different heights therein, a chamber above the lower of said burners and provided with a cold-water inlet and an outlet, and a pair of chambers in communication with each other and respectively disposed above said first-mentioned chamber and the upper of said burners, one such last-mentioned chamber having a cold-water inlet and the other an outlet, and means for connecting said outlets.

9. A heater comprising a casing, a pair of burners disposed at different heights therein, a chamber above the lower of said burners and provided with a cold water inlet and a hot water outlet, and a pair of chambers in series communication with each other and respectively positioned above and below the upper of said burners, the lower of said series chambers having a cold water inlet, the upper of said series chambers having a hot water outlet.

10. A heater comprising a casing, a pair of burners disposed at different heights therein, a chamber positioned above the lower of said burners and provided with a cold-water inlet and an outlet, a second chamber positioned above said first-mentioned chamber and provided with a cold-water inlet, a third chamber communicating with said second chamber and positioned over said upper burner, said last-mentioned chamber being similarly provided with an outlet, and a pipe communicating with each of said outlets.

Signed by me, this 5th day of October, 1911.
